UNITED STATES PATENT OFFICE.

GEORGE H. ALLEN, OF CLINTON, NEW YORK.

WEATHERPROOF SIGN.

Application filed November 19, 1926. Serial No. 149,489.

The invention aims primarily to provide a new and improved form of weatherproof sign, of laminated nature, and of such construction that it may be easily and inexpensively manufactured, yet will be durable and very desirable, whether it is to be illuminated or not illuminated, as desired.

With the foregoing in view, the invention resides in the novel subject matter herein-
10 after described and claimed, the description being supplemented by the accompanying drawing.

Fig. 1 is an elevation of a sign constructed in accordance with the invention.

15 Fig. 2 is a sectional view illustrating the fabric sheet and the paper sheet, preparatory to uniting them by means of the coating.

Fig. 3 is a sectional view through a portion of the completed sign, it being of course understood that both Figs. 2 and 3 are greatly exaggerated for illustrative purposes.

In manufacturing the sign, I take a sheet 20 of woven textile fabric, paper or other translucent material and also an opaque sign sheet preferably of paper with the sign characters cut therefrom and dip both while superimposed in hot paraffine or other waterproofing substance to impregnate these sheets and to provide a coating 6 on both sides thereof. Then, after hardening of the coating 6, I press the two, coated and impregnated sheets tightly together, if necessary with a hot iron, causing the two sheets 25 to be effectively united.

By providing the novel subject matter herein shown and described, a sign is provided which may be easily and inexpensively manufactured, will be durable when used out 30 of doors, and will be generally desirable

from a number of standpoints. The sign 5 is effectively reinforced by the fabric sheet 4 and both sheets are effectively covered and protected, so that they cannot swell or otherwise distort, even when used in exceptional-
45 ly damp places. By having the sign characters cut from an opaque sheet, all light leaving the illuminated sign box must come through the characters, thus giving them greater brilliancy.
50

I claim:

1. A weatherproof sign consisting of a translucent sheet and an opaque sign sheet having sign characters cut therefrom, the two sheets being superimposed and impregnated and coated with a waterproof coating which unites them.
55

2. A weatherproof sign consisting of a flexible imperforate translucent sheet impregnated and coated on both sides with 60 waterproof material, and a flexible opaque sign sheet having cutout sign characters, said sign sheet being impregnated and coated on both sides with waterproof material, the two sheets being secured to each other by 65 means of their coatings.

3. A weatherproof sign consisting of a flexible imperforate translucent sheet of textile fabric impregnated and coated on both sides with paraffine, and a flexible opaque 70 sign sheet formed of paper and having cutout sign characters, said sign sheet being impregnated and coated on both sides with waterproof material, the two sheets being secured to each other by means of their coatings.
75

In testimony whereof I have hereunto affixed my signature.

GEORGE H. ALLEN.
